UNITED STATES PATENT OFFICE.

JAMES A. BUCHNER, OF MAQUOKETA, IOWA.

FOLDING FLORAL-DISPLAY RACK.

1,078,248.

Specification of Letters Patent. Patented Nov. 11, 1913.

Application filed July 26, 1913. Serial No. 781,396.

To all whom it may concern:

Be it known that I, JAMES A. BUCHNER, a citizen of the United States, residing at Maquoketa, in the county of Jackson and State of Iowa, have invented certain new and useful Improvements in Folding Floral-Display Racks, of which the following is a specification, reference being had to the accompanying drawings.

10 This invention relates to display stands and racks, and it more particularly relates to an improved form of folding floral display racks.

One of the objects of the invention is to 15 provide a display rack of this character which is especially adapted for use by undertakers, for supporting and displaying wreaths, garlands and other floral display at the residence of the deceased, at the 20 church and at the cemetery, before the flowers are finally laid upon the grave.

Another object of the invention is to provide a display rack of this character with 25 inclined shelves, or rack members, the inclination of which is sufficient to effect the best possible display of the flowers, without allowing the flowers to slide from the inclined surface.

Another object is to provide a display 30 rack of this character which may be quickly and easily folded compactly into a comparatively small space and which is light, strong, rigid, comparatively inexpensive, and thoroughly practical and efficient.

35 In the accompanying drawings, which supplement this specification, Figure 1 is a side elevation view, illustrating the device in full lines in operative position, and in dotted lines in folding position, certain 40 parts of the frame being broken out for the purpose of disclosing other parts; Fig. 2 is a view, at right angles to Fig. 1, of the device in folded position; Fig. 3 is a view somewhat similar to Fig. 2, certain parts being broken away and certain parts being 45 shown in dotted lines; Fig. 4 is a sectional view taken on the line 4—4 of Fig. 1; Fig. 5 is a fragmentary detail view; Fig. 6 is an

enlarged perspective view of one of the slotted and normally inclined shelf or rack elements; and Fig. 7 is a side elevation view of the device in folded position, the lower end being broken off.

In these drawings, in which similar reference characters correspond with similar parts throughout the several views, the rack consists essentially of two opposite vertical standards 10 and 10', two opposite inclined supporting beams 11 and 11', two pivotally mounted supporting yokes 12, two pivotally mounted shelf members 13, and a combined shelf member and hinge-jointed stay member 14. The standards 10 and 10' are connected adjacent to their upper ends by means of a horizontal brace rod 15, while a combined brace rod and pivot member 16 connects them adjacent to their lower ends, and a combined pivot and brace member 17 connects them together between the members 15 and 16, and adjacent to the upper ends thereof. The members 11, 11' and 13 have their rear upper ends pivotally connected to the members 10 and 10' by means of the member 17, while the member 14 is pivotally connected to the members 10 and 10' by means of the member 16. The forward end portion of the member 14 is pivotally connected to the members 11 and 11' by means of a combined pivot and brace rod 18, the lower yoke 12 being also pivotally mounted on the member 18, its lower ends being seated between the inner surfaces of the members 11 and 11' respectively and the outer surfaces of the member 14. A combined pivot and brace member 19 connects the members 11 and 11' approximately half way between the members 17 and 18, and the lower shelf member 13 is pivotally mounted on the member 19, while the lower ends of the upper member 12 are pivotally seated on the pivot rod 19 between the inner surfaces of the members 11 and 12 and the outer surfaces of the lower member 13.

Each yoke 12 preferably consists of two side elements 20 and 20' respectively, rigidly connected together by means of a com-

bined brace and pivot rod which constitutes a portion of said yoke, while the frame members 13 consist of several longitudinally slotted bars 22, 22' and 22^a respectively. 5 While I have shown but three of these slotted bars, it is obvious that I may provide any desired number of such bars, or may use any proper auxiliary means for reducing the amount of space between these bars, for 10 properly supporting the floral display.

The pivot members or rods 21 extend through the slots 23 of the respective shelf members 13, and normally rest in the upwardly extending notch or seat 24, so as to 15 positively and securely prevent the yokes from accidental movement relative to the shelf members when in use. The rear end of the upper shelf member is pivotally mounted on the member 17 inwardly of the 20 members 11 and 11', while the rear end of the member 14 comprises a pair of links 14' which have their rear ends pivotally mounted on the rod 16, while the forward ends of these links are pivotally connected with the 25 substantially horizontal shelf member by means of a pivot rod 25. This substantially horizontal shelf member comprises a frame consisting of two parallel bars 14^a and 14^b having their front ends connected by means 30 of a brace rod 26 and shelf elements or slats 27, while their rear ends are connected by means of the pivot member 25 which constitutes a part of said horizontal frame or shelf member. The forward end portion of 35 the horizontal frame extends forwardly beyond the members 11 and 11', so as to constitute a shelf on which flowers may be displayed, while at the rear end of this shelf, and forwardly of the hinge joint or pivot 40 element 25, the members 14^a and 14^b are pivotally mounted on the rod 18.

The shelf members 13 are each provided with a laterally and horizontally extending slat 27, similar to those on the member 14, 45 and as many of these slats may be employed as may be found desirable, but in the present instance, the slats are disposed only upon the forward ends of the respective shelf members, and provide stops, for preventing 50 the floral display from sliding off of the shelves.

The application and use of the device will be clearly obvious to those familiar with the art, from an inspection of Fig. 1 in connection 55 with the foregoing description.

When it is desired to fold the device, it is only necessary to slightly raise the forward ends of the shelf members 13 and push the upper ends of the members 12 rearwardly, so that the members 21 slide in the 60 slots 23 until the members 11, 11', 12 and 13 lie in the same common plane; then raise the hinge joint 25, which may be done by

pressing the foot upon the slats 27 of the member 14, thereby swinging the members 10, 10' and 14' into the same plane, while the members 14^a and 14^b lie at a very slight angle to the plane of the members 11 and 11', and these latter members are at a very slight angle to the plane of the members 10 70 and 10', as illustrated in Figs. 5 and 6.

As the slots 23 extend through the major portion of the respective bars, and a large percentage of the material is removed from these bars, in the provision of these slots, 75 it is seen that the weight of the rack is greatly diminished, so that the device may not only be easily handled, but may also be conveniently carried in the floral conveyance of the undertaker. The ends of the 80 bars 22 and 22^a are beveled, as at 22^b so that when the device is folded, these elements 22^b of the upper shelf member rests against the rear end of the lower shelf member 13, so as to prevent the movement of this shelf 85 member beyond the common plane of the shelf members and supporting beams.

It will be seen that I have provided a display rack of this character especially applicable for the purpose specified, and the 90 device is not limited by this specific use.

While the accompanying drawings illustrate what I believe to be the preferred embodiment of my invention, it is to be understood that the invention is not limited thereto, but that various changes may be made in the construction, arrangement and proportions of the parts without departing from the scope of the invention, as defined in the appended claims. 100

I claim:

1. In a folding display rack, a pair of substantially vertical standards, a pair of inclined supporting beams, a forwardly and downwardly inclined shelf member, a pivot member connecting the standards and pivotally connected to an end respectively of the inclined supporting beams and shelf member, said shelf member being provided with a longitudinal slot, and a forwardly and upwardly inclined yoke pivotally connected to the inclined supporting beams and engaged with the slot of said shelf member and adapted to slide rearwardly therein, so that the said inclined shelves may be 115 swung downwardly and folded with the supporting beams and yoke into such relation that they lie in a common plane.

2. The combination in a folding display rack, of a pair of substantially vertical standards, a pair of inclined supporting beams having their upper ends pivoted to the standards, a hinge-jointed member pivotally connected to the lower portion of the standards and to the lower portion of the inclined 120 supporting beams, a plurality of forwardly

and downwardly inclined shelf members pivotally connected to the supporting beams, and a forwardly and upwardly inclined yoke member movably connected to each of the inclined supporting beams and to each shelf member for supporting the latter so that the shelf members may be folded in the same plane with the standards and with said supporting beams, said hinge-jointed member being adapted to be folded approxi-

mately in the same plane of the supporting beams and to allow the supporting standards to be swung approximately into the same common plane therewith.

In testimony whereof I hereunto affix my 15
signature in the presence of two witnesses.

JAMES A. BUCHNER.
